[57] CLAIM

The ornamental design for a combined slow speed vertical air circulating fan and light fixtures, as shown and described.

DESCRIPTION

FIG. 1 is a perspective view of a combined slow speed vertical air circulating fan and light fixtures, showing my new design;

FIG. 2 is an enlarged end elevation view thereof, the opposite end being a mirror image of that shown; and FIG. 3 is an enlarged side elevation view thereof, the opposite side being a mirror image of that shown.

FIG. 1

FIG. 2

FIG. 3
